UNITED STATES PATENT OFFICE.

CHARLES E. GIERDING, OF MANSFIELD, OHIO, ASSIGNOR TO THE OHIO BRASS COMPANY, OF MANSFIELD, OHIO, A CORPORATION OF NEW JERSEY.

TROLLEY-BASE.

1,172,786.

Specification of Letters Patent. Patented Feb. 22, 1916.

Application filed March 5, 1913. Serial No. 752,043.

To all whom it may concern:

Be it known that I, CHARLES E. GIERDING, a citizen of the United States, residing at Mansfield, in the county of Richland and 5 State of Ohio, have invented certain new and useful Improvements in Trolley-Bases, of which the following is a true, clear, and exact specification.

One of the objects of my invention is to 10 provide an improved trolley base which will be simple, durable and reliable in construction, and effective and efficient in operation.

A further object of my invention is to 15 provide an improved trolley base wherein the various strains and shocks to which the device is subjected during operation or when the trolley leaves the wire, will be neutralized or balanced, thereby minimizing the damage and wear and tear resulting from 20 such strains and shocks, and rendering the structure extremely sensitive and responsive to the variations in the trolley wire and the relative movements of the car.

A further object of my invention is to 25 provide an improved trolley base which will be adjustable in its several parts so that the degree of sensitiveness of the device may be accurately regulated.

A further object of my invention is to 30 provide an improved trolley base in which the various parts making up the complete structure will be interchangeable so that they may be renewed or replaced at slight expense whenever damaged, my purpose being further to provide an improved structure of this character which may be readily assembled or disassembled by a person unskilled in the art without the necessity of special tools.

40 A still further object of my invention is to provide an improved trolley base which may be readily locked or secured in condition to facilitate the removal or renewal of a bent or damaged trolley pole, especially 45 when the car is standing in repair shops or sheds having low head-room.

A still further object of my invention is to 50 improve the trolley base structure constituting the subject matter of Patent Number 1,033,166, granted to me July 23, 1912.

Other objects of my invention will appear hereinafter.

55 My invention consists in the features of novelty in the constructions, combination and arrangement of parts herein described,

and shown in the accompanying drawings which illustrate one embodiment of my invention, and more particularly set forth in the appended claims.

In the drawings, 60 Figure 1 is a top plan view of a structure embodying my invention, the service springs thereof being shown partly in diagram for the purpose of more clearly disclosing the other parts of the device. Fig. 2 is a longitudinal central sectional view, taken on the line 2—2 of Fig. 1. Fig. 3 is a transverse vertical sectional view taken substantially on the line 3—3 of Fig. 1. Fig. 4 is an enlarged detail view of the trolley pole 70 fork and the service yoke in their relative positions, other parts being omitted for the sake of clearness. Fig. 5 is an enlarged detail view of one of the lateral extensions of the trolley pole fork upon which one end 75 of the service springs is anchored. Fig. 6 is a detailed transverse sectional view on the line of 6—6 of Fig. 2, and Fig. 7 is a fragmentary bottom view of base plate showing 80 the lock for holding the turret in place.

In the accompanying drawings I have 85 illustrated my invention as embodied in a structure which in practice I have found best adaptable to various conditions and requirements such as manufacturing and operating, but it will be obvious to one skilled in the art after having obtained an understanding of my invention from the disclosures herein made that my invention is 90 equally as capable of embodiment in other structures without departing from the spirit and scope thereof.

The structure shown in the drawings is 95 of the type which is adapted for mounting upon the roof of the car and for maintaining the trolley in yielding relation to the trolley wire under such variations and conditions as are usually found in practice. This structure has a broad flat base A provided with bolt holes A¹ permitting it to be securely fastened to the top of the car. Rising vertically from this base and preferably formed integrally therewith is a hollow turret post or standard A² which is circular in section and which serves as a central member around which the several operating parts rotate in adapting themselves to the movements of the car relative to the trolley wire. A hollow, inverted member B forming a turret is mounted to rotate upon the 100 105 110

post or standard A², and bearings, such as vertical roller bearings B¹, are provided to reduce friction incident to the rotary action of the turret. Any suitable means may be employed for holding the turret in position. In the structure shown I use a central bolt C which screws at its upper end in the head B² of the turret and which extends downwardly through the central bore C³ of the post A². The lower end C of the bolt has a head B³, and the lower end portion C⁴ of the post bore, although slightly contracted, is sufficient in diameter to allow the bolt-head B³ to be passed freely through it. In the under side of the base-plate I provide a strip or bar of metal A³ slidable horizontally in a suitable groove, and having a forked or slotted end A⁴ (Figs. 2 and 7) adapted to embrace the bolt C just above its head and thus lock the turret against vertical displacement. This, however, does not interfere with the rotation of the turret. The locking member may be fastened in position by means of a small screw A⁵. This arrangement permits the turret to be conveniently removed for the purpose of cleaning or repair. Another important advantage lies in the fact that, as will later appear, the various operating parts are all mounted upon or supported by the turret, and may be readily removed therewith as a unit, thus facilitating the quick interchanging of trolley mechanisms without detaching the base from the car whenever the occasion requires. In the structure shown the trolley pole is supported at an angle to the car by a swinging fork or member D, which has an elongated socket or bore D¹ for receiving the lower part of the trolley pole. This socket forming portion is preferably split into two separable sections, as shown, whereby the trolley pole may be conveniently detached as desired. The fork D is in general U-shaped and embraces the upper portion of the turret upon which it is mounted. It will be seen that the upper portion of the turret has a horizontally disposed bearing portion 1. This carries a short removable shaft or axle 2, projecting beyond the ends of the bearing and forming pivotal supports for the parallel or side portion D² of the trolley fork. In order that these parts may be readily assembled or disassembled without the necessity of any special tools I cut a slot D³ in the central portion of the journal bearing 1 to accommodate a cotter pin D⁴ which passes through a suitable hole in the shaft 2 and projects into said slot. This simple arrangement firmly holds the shaft and consequently the fork in their relative operating positions. The removal of the single cotter pin D⁴ unlocks the shaft and permits the parts to be readily disassembled.

The free ends 5 of the trolley fork project beyond or below the pivotal axis of the trolley fork. These ends 5 have laterally projecting stud shafts or pins 6 to which the ends of a number of service springs S are anchored. These service springs, acting on the pivoted fork, hold the trolley in yielding engagement with the trolley wire and allow the trolley to rise and fall in accordance with the variations in the relative height of the trolley wire as the car travels. The springs may be of any suitable design for the purpose and any desired number or arrangement. In carrying out the idea of a balanced or equalized structure I prefer, however, to use two sets of two springs each, one set thereof being disposed on either side of the turret and all of said springs lying substantially in the same horizontal plane. The springs are preferably made in the form of elongated spirals having eyelets or loops 7 and 8 formed at their respective ends.

As before mentioned the ends 7 of the service springs are anchored on the studs 6 which project laterally from the trolley fork. I provide on each of these studs 6, a rotatable sleeve 9, having a longitudinal slot 10 extending through to the stud. The sleeves are held in place on the studs by small lugs 11 formed at the ends of said studs, and they can only be removed from or placed on the studs by rotating them until the slots 10 register with the lugs 11 (Figs. 1 and 5). The loop ends 7 of the service spring encircle these sleeves, each sleeve being adapted to accommodate the two springs of each set. A portion of the periphery of the sleeves on the rear sides thereof are provided with grooves 12 wherein the loops 7 are seated, and the grooves are eccentrically disposed with relation to the remaining peripheral portions of the sleeves so that the tension exerted by the service springs on the sleeves prevents the sleeves from turning in the loops and becoming accidentally unlocked from the studs. During the operation of the device, however, the sleeves rotate to a certain extent on the studs, due to the varying angular relation between the trolley fork and the service springs, and thereby constitute bearings for the loop ends of the springs to take up such wear as the loop ends of the springs and studs would otherwise be subjected to if the loop ends of the springs were placed directly on the studs. It is seen that the grooves 12 and slots 10 of the sleeves and the lugs 11 are relatively so positioned with respect to each other that the sleeves are held against displacement on the studs by the lugs 11 (Fig. 5), but in the event that it is desired to remove the sleeves, it is simply necessary to relieve the tension and unhook the springs, when the sleeves may be rotated with the springs until the slots 10 and the

lugs 11 permit the longitudinal removal thereof. This construction has the decided advantage that the wear on the loop ends of the springs is entirely eliminated, and the 5 wear on the studs is minimized due to the pressure of the loop ends of the springs being distributed by the sleeves throughout their entire length. The other loop ends 8 of the service springs, as will be seen more 10 particularly in Fig. 1, are removably anchored on the hooked ends (15) of a crosstree or tail bar 26 which is supported by a substantial horizontal service yoke. Referring to Fig. 1, it will be seen that the 15 service yoke is in the form of a loop shaped member, the main side portions 20 of which are substantially parallel and lie outside of or embrace the turret, but lie inside or 20 between the arms of the trolley fork D. The forward ends 21 of these side bars turn 25 inwardly and then continue forward to form a narrower forward loop 22. The rear ends of the parallel side bars 20 of the yoke merge together in a single rearwardly projecting tail piece 23 which is dropped slightly below the plane of the forward loop 22 and which preferably inclines slightly upwardly. This tail piece is preferably hollow and rectangular in section and telescopes 30 within the hollow rectangular stem 24 of the tail member 26 both parts being made rectangular to prevent relative rotary movement. The purpose of this arrangement is to provide 35 for the accurate regulation of the tension of the service springs.

The tail member has a central opening 27¹ through which an adjusting bolt 27 freely passes and extends longitudinally within the stem 24 and tail piece 23 where 40 it engages with or operates against a partition or abutment 28 in said tail piece. Just behind the opening 27 is a threaded square nut 29 of a size to fit easily within said hollow stem. The bolt is threaded through this 45 square nut so that by rotating it in one direction or the other it will operate to move the tail member 26 longitudinally in either direction depending upon the direction of the rotation of the bolt and thereby vary 50 the tension of the service springs S. A lock nut 30 may be provided on the bolt for the purpose of locking the bolt and the tail member 26 in their adjusted position. This arrangement has the advantage of being 55 simple in construction and the parts are interchangeable so that those parts (the nut 29 and the bolt 27) which are subjected to the wear, may be renewed at slight expense. In other words, if the bolt member 27 were 60 threaded directly through the tail member 26 it is readily seen that the wearing or stripping of the threads in said tail member would necessitate the renewal of the entire tail member, whereas by the present construction this expense is eliminated.

In the structure shown the service yoke is supported by the shaft or axle 2 which passes through openings 31 in the side members 20 of the service yoke, near the upper edges thereof. It will be noted that these 70 openings or slots 31 are elongated so as to permit a limited longitudinal movement of the yoke. The yoke is also loosely supported at its forward end by a bolt or bar 35 which passes horizontally through the 75 head of the forward loop 22. The rod 35 is threaded into a socket in the end of and rigidly supported by a round stud 36 formed integral with and projecting horizontally from the turret member B. In 80 order not to interfere with the longitudinal movement of the yoke, I place a sliding collar or sleeve 37 on the rod 35. This sleeve passes through a slightly larger opening 38 in the head of the forward loop 22 which 85 allows a slight rotary movement of the yoke about the pivot shaft and facilitates a better equalization of shocks. The sleeve 37 has a flange 39 against which said head abuts and between this flanged collar and 90 the turret is a strong buffer spring S¹. It frequently happens that the trolley leaves or "jumps" the trolley wire and the trolley pole under the influence or action of the service springs is swung or thrown violently 95 forward. The momentum acquired often carries the trolley pole so far over that the pole is bent or broken and the other parts of the structure are subjected to damaging shocks. The structure which I have shown 100 eliminates these objections. The buffer spring S¹ absorbs these various shocks and brings the trolley pole to a stop gradually, and the entire structure is so arranged that the strains are equalized or balanced to such 105 an extent that no damage whatever is done. In the structure shown the buffer spring, as before mentioned, is in the form of a spiral coil encircling the stud 36 and rod 35 and is positioned between the turret and the 110 collar or sleeve 37 hence when the service yoke is moved or shifted bodily rearward the buffer spring will be compressed. In order, therefore, to communicate the shock of the rapidly moving trolley pole to the 115 yoke whereby the shock may be absorbed by the buffer spring, I provide the lower ends 5 of the trolley fork with instanding buffer lugs or projections 40 which strike or engage shoulders 41 on the main service yoke 120 adjacent its lower edges. These shoulders 41 are formed by the inturned ends 20 of the service yoke at some distance below the pivotal axis of the trolley fork, hence when the buffer lugs 40 strike these shoulders the 125 service yoke is shifted horizontally rearwardly and the compression of the buffer spring absorbs the shock and brings the trolley pole gently to rest. It will be observed that the faces of the shoulders 41 130

are substantially in a vertical line passing through the pivotal axis of the trolley fork and that the buffer lugs 40 on the trolley fork are disposed sufficiently forward on the 5 yoke to not interfere with the normal operation of the trolley pole (see Fig. 4). Since the buffer lugs are on the fork they necessarily move through an arc and they engage the shoulders 41 when they are moving through the lowest point in said arc. For a short distance on each side of this 10 lowest point the movement of the buffer lugs amounts practically to a straight horizontal line parallel with the line of movement with the main service yoke. In consequence of this arrangement and proportion of the parts the main service yoke is shifted 15 longitudinally and is not subjected to any lateral or vertical strains, hence I have found that in practice I am able to dispense 20 with any devices or mechanism for taking up lateral or vertical strains on the main service yoke. The advantage of my improved construction over the various types 25 of trolley bases now on the market is marked in this respect. The shocks on the apparatus are concentrated along the horizontal line of movement of the main service yoke in such manner as to be directly and completely 30 absorbed by the buffer spring and at the same time the entire structure is entirely unhampered in its rotary or "turret" movement. Another important feature of my improved structure lies in the fact that as 35 before intimated the parts are so proportioned that when the buffer spring and service yoke come into operation to take care of the abnormal movement of the trolley pole, the service springs S are in such position as to exert no tension upon the trolley pole. In other words, at the time the buffer lugs 40 strike the shoulders 41 the service 40 springs will cease to urge the trolley pole forward, hence the buffer spring will not have to counteract any then existing force 45 of the service springs.

It is very frequently found necessary to replace or renew bent or damaged trolley poles while the cars are in the repair shops 50 or sheds, but these repair shops generally have such low head room, that it is impossible to raise the pole to the position wherein the service spring tension is released as is the usual custom, and therefore, when bent 55 or damaged poles are renewed in the shops, the trolley poles must be pulled down close to the top of the car. Furthermore, the powerful action of the service springs renders it not only difficult but actually dangerous to attempt to remove the trolley pole 60 from its yoke without in some way fastening or locking the fork. I have provided a simple form of lock for this purpose. Referring more particularly to Fig. 2 it will be seen 65 that on the rear side of the turret is a ver-

tically movable latch or hook H mounted between two outstanding lugs H¹ on the turret. A pin passes between these two lugs and through an opening H² in the latch H. This opening or slot H² is elongated so that the 70 latch may be raised or lowered vertically a considerable distance. This may be accomplished by forming the lower portion of the edge H³ at an angle to the remaining portion H⁴ of said edge, and also placing the 75 lower portion of the slot at a corresponding angle, thereby making it necessary to lift the latch vertically a certain distance before it can be swung outwardly away from the turret. In order to lock the trolley fork it 80 is simply necessary to pull it down close to the top of the car and then lift the latch H and hook it over the top edge H⁵ of the trolley fork. With the trolley fork thus locked the work of removing or replacing a 85 trolley pole is rendered extremely convenient and easy. Obviously however the lock does not interfere with handling of trolley poles in the case of long cars where two trolley poles are employed and the one not in use is 90 fastened down close to the car by a hook or other means which engages the trolley pole further out near its end. The fact that this latch does not interfere with operating conditions is obvious since the trolley fork clears 95 the latch completely when the latch is in its normal position, as shown in Fig. 2.

I claim:

1. In the structure of the class described, the combination of a stationary base, a yoke member rotatively mounted on said base, trolley pole mechanism pivotally mounted on said yoke and operable through an arc of movement, service spring mechanism connected to said trolley pole mechanism and 100 constantly tending to rotate it about its pivot, means on said trolley pole mechanism for shifting said yoke member longitudinally when said trolley mechanism is moving through a portion of its arc substantially 105 parallel with the direction of movement of said yoke member and means yieldingly resisting the movement of said yoke member.

2. In a structure of the class described, the combination of a support, a member longitudinally shiftable on said support, a trolley pole device pivoted on said support, spring mechanism normally tending to rotate said trolley pole device on its pivot through a certain arc, means on said trolley 115 pole device for engaging and shifting said member longitudinally at the time said means moves substantially parallel with the direction of movement of said member, and a buffer spring acting on said member to resist the longitudinal movement thereof.

3. In a structure of the class described, the combination of a supporting base, a turret member rotatably mounted on said base, a trolley arm pivotally mounted on said tur- 130

ret member, service spring mechanism acting on said trolley arm to maintain it in operative relation to the trolley wire, a movable member mounted on said turret and adapted to be shifted by said trolley arm when the trolley arm is in that abnormal position wherein its line of movement and that of said movable member substantially coincide, and a buffer spring adapted to oppose said movable member.

4. In a structure of the class described, the combination with a stationary base, turret rotatably mounted on said base, a trolley pole fork pivoted on said turret, a spring mechanism tending to swing said trolley fork on its pivot, a yoke member mounted upon said turret, means on said trolley fork placed to correspond with an abnormal position of said trolley pole fork and adapted when the arc of movement of said means substantially coincide with the line of movement of said yoke member, and a buffer spring constantly opposing the movement of said yoke member.

5. In a structure of the class described, a stationary supporting base, in combination with a rotary turret mounted thereon, a bearing formed on said turret, a transverse shaft journaled therein, a yoke flanking said turret and rotatable therewith and having a slotted connection with said shaft to permit its longitudinal movement, a head formed at one end of said yoke, a heavy buffer spring interposed between said head and said turret for opposing the movement of said yoke, a forked trolley arm pivoted on said shaft and having buffer lugs projecting beyond said shaft, buffer shoulders formed on said yoke and disposed in a line

passing through the axis of said shaft perpendicularly with respect to the line of longitudinal movement of said yoke, said shoulders being adapted to be struck by the buffer lugs of said trolley arm when the arm reaches an abnormal position and service spring mechanism acting on said arm and tending to swing it into said abnormal position.

6. In a structure of the class described, a stationary supporting base, in combination with a rotary turret mounted thereon, a bearing formed on said turret, a transverse shaft journaled therein, a yoke flanking said turret and rotatable therewith and having a slotted connection with said shaft to permit its longitudinal movement, a head formed at one end of said yoke, a powerful buffer spring interposed between said head and said turret for opposing the movement of said yoke, a forked trolley arm pivoted on said shaft and having buffer lugs projecting beyond said shaft, buffer shoulders formed on said yoke and disposed in a line passing through the axis of said shaft perpendicularly with respect to the line of lon-

gitudinal movement of said yoke, said shoulders being adapted to be struck by the buffer lugs of said trolley arm when the arm reaches an abnormal position, a longitudinally adjustable tail member on the rear end of said yoke and a plurality of service springs connected between said tail member and said trolley arm and tending to swing said arm to said abnormal position.

7. In a structure of the class described, a stationary supporting base in combination with a turret rotatably mounted thereon, a yoke member flanking said turret and having a head formed on its forward end, a tail formed at the rear end of said yoke, a longitudinally adjustable tail member mounted on said tail, a bearing formed on said turret, a transverse shaft mounted in said bearing and passing through slots in said yoke to permit a limited longitudinal movement of said yoke, a forked trolley arm spanning said turret and pivotally mounted upon said shaft, buffer lugs formed on said trolley arm beyond said shaft, buffer shoulders formed on said yoke in a line passing through the axis of said shaft perpendicularly with respect to the line of movement of said yoke and disposed in the path of said buffer lugs, a plurality of service springs connected between said tail member and said forked trolley arm tending to throw said trolley arm forward about its pivot into an abnormal position, and a buffer spring interposed between said turret and said yoke head for opposing the movement of said yoke and absorbing the shock incident to the buffer lugs striking said shoulders.

8. In a structure of the class described, a stationary supporting base in combination with a turret rotatably mounted thereon, a yoke member flanking said turret and having a head formed on its forward end, a tail formed at the rear end of said yoke, a longitudinally adjustable tail member mounted on said tail, a bearing formed on said turret, a transverse shaft mounted in said bearing and passing through slots in said yoke to permit a limited longitudinal movement of said yoke, a forked trolley arm spanning said turret and pivotally mounted upon said shaft, buffer lugs formed on said trolley arm beyond said shaft, buffer shoulders formed on said yoke in a line passing through the axis of said shaft perpendicularly with respect to the line of movement of said yoke and disposed in the path of said buffer lugs, a plurality of service springs connected between said tail member and said forked trolley arm tending to throw said trolley arm forward about its pivot into an abnormal position, a buffer spring interposed between said turret and said yoke head for opposing the movement

of said yoke and absorbing the shock incident to the buffer lugs striking said shoulders, a central slot in said bearing and a single removable pin positioned in said slot 5 and passing through said shaft for locking the shaft into position.

9. In a structure of the class described, a supporting base in combination with a rearwardly extended member mounted upon 10 said base, a forked trolley arm pivoted upon said base, a tail member telescoped with said rearwardly extended member, tension springs extending between said tail member and said forked trolley arm for actuating 15 said trolley arm, a removable member carried by said tail member and a bolt threaded through said removable member and acting against said rearwardly extended member for relatively moving said tail member to adjust the tension of said springs. 20

10. In a trolley base of the class described, the combination of two telescoping members relatively movable with respect to each other, means on one of said members for 25 anchoring the tension springs thereto, a threaded member removably mounted in one of said members, an abutment formed on said other member and an adjusting bolt threaded through said threaded member and 30 acting against said abutment for moving said members relatively to each other.

11. In a trolley base of the class described, the combination of two hollow bars of substantially rectangular cross section telescoped one within the other, an abutment formed in one of said hollow bars, a threaded member detachably held in said other bar, a bolt operating said threaded member and extending longitudinally of said bars 35 into engagement with said abutment for adjusting said bars relatively to each other, and means on one of said bars to which the spring tension mechanism of the trolley base 40 may be anchored.

45 12. In a structure of the class described, a supporting base, in combination with a forked trolley arm pivotally mounted there-

on and having a laterally projecting stud, a slotted sleeve rotatably mounted on said stud, a lug on said stud for holding said 50 sleeve thereon but permitting the sleeve to be removed when the slot and lug register, and a tension spring having a loop end encircling said sleeve.

13. In a structure of the class described, a 55 supporting base, in combination with a forked trolley arm pivotally mounted thereon and having a laterally projecting stud, a slotted sleeve rotatably mounted on said stud, a lug on said stud for holding said 60 sleeve thereon but permitting the sleeve to be removed when the slot and lug register, an eccentrically disposed groove formed in a periphery of said sleeve, and a tension 65 spring anchored at one end and having a loop end encircling said sleeve and seating in said groove, whereby the tension of said spring on said sleeve will prevent relative movement of the sleeve in said loop.

14. In a structure of the class described, 70 a supporting base in combination with a forked trolley arm pivotally mounted upon said base and having laterally projecting studs, rotatable collars mounted upon said studs, eccentric grooves formed in the peripheries of said collars, tension springs anchored at one end and having looped ends 75 encircling said collars and seated in said grooves, said springs exerting a force upon said trolley arm to rotate it about its pivot, 80 lugs formed on said studs for preventing the said collars from slipping off said studs, and slots in said collars permitting the removal thereof when said slots are brought into register with said lugs. 85

In testimony whereof I have signed my name to this specification, in the presence of two subscribing witnesses, on this 21st day of Feb. A. D. 1913.

CHARLES E. GIERDING.
